(57) CLAIM

The ornamental design for a bottle, as shown and described.

DESCRIPTION

FIG. 1 is a front perspective view of a bottle showing my new design;

FIG. 2 is a rear perspective view thereof;

FIG. 3 is a right perspective view thereof;

FIG. 4 is a front view thereof;

FIG. 5 is a back view thereof;

FIG. 6 is a left view thereof, the right view being a mirror image thereof; and,

FIG. 7 is a top view thereof.

All sides not shown form no part of the claimed design. The broken line showing of the crescent is for illustrating portions of the bottle and forms no part of the claimed design.
